UNITED STATES PATENT OFFICE.

EDWARD E. JOHNSON, OF ST. PAUL, MINNESOTA.

WATER-COLUMN.

1,391,545.

Specification of Letters Patent. Patented Sept. 20, 1921.

Application filed April 29, 1917. Serial No. 163,432.

To all whom it may concern:

Be it known that I, EDWARD E. JOHNSON, a citizen of the United States, residing at St. Paul, in the county of Ramsey and State of Minnesota, have invented certain new and useful Improvements in Water-Columns, of which the following is a specification.

My invention relates to water columns, and has for its object to provide a novel construction wherein a curved and extended delivery pipe preferably of sheet metal or other relatively light substance is attached to the upper end of a vertical standpipe in such manner that the delivery pipe, and the discharge spout coöperating therewith, are capable of rotation upon the standpipe, about a vertical axis while the standpipe itself remains stationary.

Another important object of my invention is to provide in combination with said rotating delivery pipe means for positively locking the discharge spout when the same is swung into inoperative position parallel with the tracks in either direction, said locking means acting automatically upon the throwing back of the delivery pipe and being subject to ready release by an operative from the tender of a locomotive. A further object of my invention is to provide in combination with said rotating delivery pipe and discharge spout, valve controlling means rotatable therewith and operated from the tender of a locomotive to actuate through connections extending through or along the standpipe the water inlet valve mechanism located at the lower end of the standpipe below the level of the ground.

The full objects and advantages of my invention will appear in connection with the detailed description thereof, and are particularly pointed out in the claims.

In the drawings, illustrating the application of my invention in one form,

Figure 1 shows a side elevation of a water column embodying my invention with the delivery pipe and discharge spout in inoperative position parallel with the tracks. Fig. 2 is a fragmentary part sectional view of the union of the delivery pipe with the rotary support therefor upon the top of the standpipe showing particularly the valve operating rod and connections. Fig. 3 is an enlarged elevation view partly in section of the means for rotatably joining the discharge pipe with the standpipe. Fig. 4 is a

fragmentary plan view, partly in section, of some of the parts shown in Fig. 3. Fig. 5 is a sectional detail of a modified form of the means connecting the rotary top to the standpipe. Figs. 6 and 7 are side elevation views showing the manner of unlocking and automatically relocking the rotary top on the standpipe. Fig. 8 is a sectional elevation view showing features of the locking device. Fig. 9 is a fragmentary elevation view showing the position of the parts after the same have been unlocked and the ring 17 and 18 rotated.

A standpipe 10 communicating with a source of water supply is provided at its upper edge with a wide flange 11 to which is secured by bolts or otherwise a similar flange 12 of an extension member forming a cylindrical inner pipe section 13 and a ring 14 supported upon a multiplicity of posts 15 cast integrally with ring 14 and section 13. The ring 14 has milled in the side thereof an annular groove or ball race 16. Positioned over ring 14 is a top ring 17 having a depending annular flange 18 which entirely surrounds the ring 14 and has an inside groove or ball race 19 corresponding in size and position with the groove 16 of ring 14. A multiplicity of balls 20 in the complete raceway formed by the facing grooves 16 and 19 support the top ring 17 and flange 18 spaced from ring 14 as indicated at 21 and rotatable thereon.

A modified construction is shown in Fig. 5 in which the ring 14 has in the top thereof an annular groove 22 facing a similar groove 23 in ring 17 and forms a raceway for the balls 20. In this form, the ring 14 and posts 15 are cut away, as indicated at 25 and balls 26 are held in the cut-away portion by a flange ring 27 bolted to the bottom of depending flange 18.

In practice, however, I have found the construction shown in Figs. 3, 4, and 8 to be highly efficient and entirely satisfactory for that purpose, the balls being inserted into the assembled grooves through an opening 28 in flange 18 normally closed by a plug 29 threaded therein. With either construction the ring 17 is held in position to rotate with the greatest freedom upon the rigid ring 14 above the cylindrical section 13 by means of the ball-bearing which is completely housed and should keep in working-order indefinitely.

As best shown in Figs. 3, 5, and 8, the

top ring 17 is formed with a downwardly extending portion 30 adapted to come between stand ring 14 and a milled surface 31 on standpipe section 13, and the top ring 5 also has an annular extension 36 forming a recess in the top ring which co-acts with the face 31 to provide a stuffing box. In this stuffing box rings of packing 32 are held in position by a flanged follower 34, which is adjusted to engage the packing rings 32 with any desired pressure by means of nuts on studs 35. This forms a watertight joint between top ring 17 and standpipe section 13, and as the top ring provides 10 the support for the laterally extended top pipe hereinafter referred to, it will be apparent that this arrangement forms a watertight joint between a fixed vertical standpipe and a laterally extended top pipe rotatively supported thereon. It is important in such a construction that the stuffing box be easily accessible for maintenance or re-packing. This is effectively provided for in my construction by the arrangement of 15 posts 15, and ring 14, the lower edge of which comes in a plane above the follower 34. The means for adjusting the follower are, therefore, always accessible and the follower may readily be dropped to the dotted line position, indicated at 34^a in Fig. 8, when it is desirable to remove or change the packing. It is to be noted also that the 20 ballbearing for the ring support is substantially in a common plane perpendicular to 25 the standpipe, for which reason the relative movement of the top ring 17 on its ballbearings, and in reference to the packing joint will have the most effective possible operation. It is also to be noted that the 30 top ring is so constructed, having reference also to the stuffing box and packing, that neither standpipe water nor storm water can get in to either the bearing race or the stuffing box follower, the top ring thus having 35 the function of a water-tight housing as well as of a support for the laterally extended pipe. Secured to ring 17 by bolts 37 is a flange 38 forming a part of a cylindrical extension 39, as shown in full in Figs. 40 1 and 2, a gasket 40 between said flange and ring making a water-tight joint. A gasket 41 between flanges 11 and 12 likewise makes a water-tight joint. From the 45 above it will be apparent that the standpipe 10, pipe 13, and section 39 are connected in water-tight relation with section 39 rotatably carried in reference to the standpipe 10 and pipe 13.

The section 39 has thereon a flange 42 to 50 which is bolted a flange 43 of an extended curved delivery pipe 44. Preferably, the delivery pipe 44 will be of sheet metal connected to the wrought or cast iron flange member 43 by welding, as indicated at 55 45 in Fig. 2. Extending through stuffing boxes

formed at 46 on extension 39 is a shaft 47 having arms 48 and 49 connected to the ends thereof and extending on either side of discharge pipe 44 upwardly and outwardly from the standpipe and meeting in a bow, 70 as indicated at 50 in Fig. 1. A spring in a housing 52 carried by a bracket 53 extending from section 39 is connected by a link 54 with a cross bar 55 connecting the arms 48 and 49, and by this means said arms 75 and the shaft 47 and parts connected therewith are held in their normal inoperative position. A chain 56 connected with bow 50 is conveniently positioned for grasping by the fireman or operative upon the tender of 80 the locomotive to actuate the arms 48 and 49 and the shaft 47. As shown in Fig. 2, the shaft 47 has fast thereon an arm 57 extending within the section 39. Connected with the arm 57 by a universal or ball-and-socket 85 joint 58 at substantially the axial center of standpipe 10 is a link or rod 59 which extends to the valve mechanism, not shown. Upon the delivery pipe 44 is directly supported a discharge spout 60 of a type shown and described in my co-pending application Serial Number 134,474. On the end of pipe 44 is a bail 61 which is engaged by the hook of the operator and enables the delivery pipe 44 and the spout 60 thereon to be 95 swung from the position parallel with the track, shown in Fig. 1, to a position extending at right angles to the track to either side where the spout is operated in the manner described in my said application to 100 water the tenders of engines. It is obvious that in the swinging of the spout from the parallel to cross-track position the valve operating arm 57 will, through joint 58, rotate upon link 59 which remains connected with the valve mechanism and extending through the center of standpipe 10. The valve can then be operated by drawing down the arms 48 and 49 through chain 56.

To prevent the standpipe from getting 110 out of its position parallel with the tracks when not in use, I provide means operable from the tender for automatically locking the discharge pipe in said parallel position. Mounted upon adjacent pairs of posts 115 15, in diametrically opposite positions, by means of pivot pins 62 and 63 are two pairs of dogs 64 and 65 having over-balancing weighted ends 66 and 67 by which the feet 68 and 69 of said dogs are normally held in 120 engagement with a side each of a lug 70 which may be cast directly and extended downwardly from flange 18, as indicated in dotted lines in Fig. 9, but which preferably comprises an offset portion 171 extending inwardly from the toe end 70 of a piece 125 172 pivotally connected at 173 with the flange 18. Piece 172 has thereon oppositely extended arms 174, 175 which are engaged by compression springs 176, 177 supported 130

upon lugs 178, 179 from which extend within the springs studs 180—181.

Although two pairs of dogs are provided on diametrically opposite sides of the stand-pipe for the purpose of permitting locking action when the laterally extended discharge pipe comes into parallel track position extending in either direction, there is only one lug 70 and lug-carrying member 172. The dogs 64 and 65 are held in their normal operative position by engagement of the lower edges of ends 66 and 67 with pins 182 and 183 carried by the uprights 15 to which the respective dogs are pivoted, as shown in Figs. 6 and 9. The pivot bolts 62 and 63 of dogs 64 and 65 are spaced from the plane of rotation of the lower limit of lug 70 and extension 171 a sufficient distance to permit lug 70 to rotate with flange 18 past said pivot points and above the upper surfaces of dogs 64 and 65. From the above it will be seen that when the dogs are in normal position with the lug 70 between them the flange 18, section 39, and delivery pipe 44, will be held locked in position and thus positioned will be parallel with the tracks in one or a diametrically opposite position. When, however, the dogs have been withdrawn from engagement with the lugs, it is apparent that upon returning the lug to locking position by rotation of the delivery pipe 44 and connected ring 17 and flange 18 the extension 171 of lug 70 will engage and ride over the surface of the dog toward which it is rotated, the other dog remaining in its position of engagement with the lower surface of flange 18. When the foot of the latter dog is engaged by the lug 70, the other dog over which said lug has just ridden will return to normal position and the discharge pipe will be held automatically locked in a parallel-track position. Because of the manner in which the said lug and extensions are held in their central position by the balanced-action of compression springs 176 and 177, it is apparent that the checking of the momentum of rotation of the parts will be effected without shock or serious reaction which would tend to injure any of said parts, which is the principal reason for applying the pivotal spring connection of the lug rather than its integral union with the flange ring 18.

Pivoted to an extension at the top of ring 17 by a pivot bolt 71 is a cam piece 72 preferably in the form of a bar having on the lower end thereof a weight 185 adjustably connected by pin-and-slot connection, indicated at 186. Secured to the cam piece 72 by angle braces or suitable means is a cam bar 73 which overlies outwardly extended toes 74 and 75 on the lower portion of feet 68 and 69 of dogs 64 and 65, as best shown in Figs. 6, 7 and 8. The cam piece is also formed at its extremity with cam notches

76 and 77 each having an abrupt end wall 78 and 79, respectively. The cam notches 76 and 77 terminate at their other ends in projections 80 and 81, which are formed at the ends of the extended cam surface provided by the lower edge of cam bar 73. An arm 82 extends outwardly from pivot 71 and has thereon a pair of hooklike extensions 83 and 84, either of which is adapted to be engaged by a hook operated from the tender of the locomotive to pull the cam member to one side or the other, as may be desired.

Referring to Fig. 3 in which dogs 64 and 65 are in locking engagement with lug 70, it is noted that the arm 82 stands vertical and the cam face 73 immediately overlies the toes 74 and 75 of the dogs. This is the normal locking position of the parts and is the position to which the parts automatically return whenever the discharge pipe is swung back into its inoperative parallel-track position. When the arm or an extension thereof as 84 is engaged so as to swing the member 72 into the position indicated in Fig. 6, (or the opposite equivalent position if the member is operated from the other of two tracks on each side of the stand-pipe) the cam face 73 engages the toes 74 and 75 and said toes ride up the cam face successively passing over the projection 80 and into the cam notch 76. This notch, like notch 77, is so formed that when the toe 74 strikes the shoulder 78, thus preventing further oscillation of cam piece 72, the toe 75 will have just passed over projection 80 and rests upon the wall of cam notch 76, and said wall will be in a substantially horizontal position, thus holding the dogs 64 and 65 correspondingly positioned so as to permit lug 70 to pass said dogs in either direction and allow the flange 18 and parts connected therewith including the discharge pipe 44 to rotate to cross-track or operative position. In this position, the dogs 64 and 65 are not only positively withdrawn from locking position but are held in that position and themselves operate through engagement with cam notch 76 and projections 78 and 80 to hold the cam piece 72 in the position shown in Fig. 6 so that the dogs 64 and 65 are held in inoperative position so long as the discharge pipe and parts connected therewith remain stationary. They are, however, free to move in either direction. Under impetus imparted by a pull on the bail 61 exerted by the fireman from the locomotive upon either track, such a pull moves pivot pin 71 carrying cam piece 72 which is capable of further axial rotation away from over the depressed toes 74 and 75, and which are thereby freed with their dogs 64 and 65 to take their normal operative position, and the cam piece 72 thus released will regain by gravity its normal inactive posi-

tion. It will be seen that while the extended discharge pipe moves through approximately ninety degrees of annular travel in changing from its parallel-track position to the cross-track position, the locking mechanism frees itself in about one-third of this movement, thus making sure being set to relock when needed.

It is, therefore, only necessary for the operative to swing the cam piece 72 into the position in Fig. 6 which can readily be done from the tender, and by engaging the bail 61 on the end of discharge pipe 44, the said discharge pipe can readily be swung into operative position. The delivery nozzle 60 supported from discharge spout 44 will then be lowered into the manhole of the tender and by pulling upon chain 56 the water valve will be operated through arms 48, 49, shaft 47, arm 57, and link 59. After sufficient water has been delivered to the tender, the chain 56 is released, the spring in the housing 52 operating to restore the valve operating parts to initial position and close the valve. The discharge spout is then slid back to its retracted position on the delivery nozzle as indicated in Fig. 1 and the fireman or operative merely pushes the delivery pipe around into position parallel with the track and the same is automatically and positively locked in said position. The operative is required only to give sufficient impetus to the discharge pipe, which rotates freely because of its relative lightness and its ball-bearing connection with the standpipe, to certainly bring the discharge pipe to the parallel-track position. If this impetus were enough to carry the discharge pipe beyond the parallel-track position, that would be immaterial as the automatic locking means would catch and hold the pipe when it reached the parallel-track position and positively lock the same in that position, the parts then taking the position indicated in Figs. 1 and 3. This is because whichever way the discharge pipe is swung the lug 70 movable with flange ring 18 will engage and depress one only of either pair of dogs 64 and 65 depending upon which way the discharge pipe is returned to initial position. The other dog of such pair will remain in its operative position, as shown in Fig. 9 where the feet 68 or 69 thereof will be engaged by a wall of lug 70, or extension 171, thus bringing the rotation of the parts to a stop, at which moment the other dog will return to normal position with its foot engaging the other side wall of lug 70 or extension 171. In this manner, the discharge pipe will have been automatically and positively locked in its parallel-track position, from which it cannot be moved excepting through operation of the unlocking cam piece 72, as in the manner hereinbefore described.

Having reference to Fig. 1, it is to be

noted that the standpipe 10 extends into a valve box or pit 100 wherein the valve casting 101 is housed and supported in a well known way. The lower end of the standpipe rests in an annular socket 102 shouledered at 103 and between the pipe and the walls of the socket is packing 104 such as oakum or any other form of packing. The standpipe in going through the box 100 passes through a collar 105 having an annular base flange 106 which is cemented into the top of the box and which has an inward annular bearing extension 107, leaving a space at 108 between the collar 105 and the standpipe 10 which is solidly filled with any desired water-proof packing material. A water-tight man-hole cover 109 closes the entrance into the box. The valve-containing box is thus hermetically sealed against the entrance of water either from the pipe or storm-water which, of course, adds to the ease of caring for the standpipe connections, and the valve mechanism prevents any formation of ice within the valve-containing box and makes it easier to prevent freezing at the valve. This is all made possible because of the fact that the standpipe 10 is permanently fixed in position, does not rotate and, therefore, can be hermetically sealed, as described or in any other equally efficient way.

The mode of operation in my improved water column has quite fully been pointed out in connection with the detailed description thereof. Its advantages lie in having very largely reduced the weight of the extended rotatable discharge pipe and its spout and mounting and of carrying this lightened load on an efficient bearing and in co-operation with an effective water-eight joint located in the plane of the forces applied by the fireman to rotate it. This is approximately twelve feet above rail under current operative conditions. It will readily be seen that such an arrangement greatly facilitates the ease with which the parts can be rotated as compared with those standpipes wherein the whole standpipe is rotated and the joint and bearing is from ten to seventeen feet below the plane of application of force by the operator. The engine tender is not infrequently covered with ice or from other causes presents an uncertain footing and it is imperative that the fireman have every advantage of easy operation of the water column, if accidents are to be avoided and train-time saved.

The construction is applicable to standpipes in use with very little modification as the pipe section 13 and parts connected therewith can be secured to the usual flange at the top of the standpipes in use. By the employment of sheet metal delivery pipe and discharge spout directly supported thereon, heavy castings and other heavy members are quite generally dispensed with

and the rotating member becomes relatively very light. The ball-bearing support for said member coupled with its lightness makes it rotate easily. The ease of rotation

- 5 necessitates positive locking means, but such locking means (and which herein forms an important part of my invention), where entirely automatic in relocking action and easily operated from the tender of the locomotive, is an additional and positive advantage of my invention. The swinging of the discharge spout into cross-track position under influence of the wind or for other reasons, where the rotating standpipe has not 10 been locked in parallel-track position, has long been a source of serious difficulty and has caused many accidents; and where devices have been employed for locking such constructions they have of necessity been 15 hand operated and located close to the ground, requiring the fireman or other operative to be down on the ground for locking and unlocking the standpipe. The simple and efficient support for the revoluble discharge pipe by a single row of balls and the 20 readily accessible and effective packing and housing construction whereby the rotating joint is made water-tight are other features of advantage of my construction, as also is 25 the valve operating mechanism with its central link and its lever system extending outwardly in proximity with the end of the discharge pipe and having revoluble connection within the pipe with said central link.

30 35 I claim:

1. A water column comprising a fixed standpipe, a laterally-extended discharge pipe carried upon and revoluble about the vertical axis of said standpipe, means for 40 positively locking said discharge pipe in a position parallel with the tracks, and a cam member pivoted to said discharge pipe operable from the tender for unlocking said discharge pipe.
2. A water column comprising a rigid vertical standpipe, a laterally-extended discharge pipe connected with the upper end of said standpipe for revolution about a vertical axis, means for automatically and positively locking said discharge pipe from revolution whenever it is brought into a position parallel with the tracks, and a cam member pivoted to said discharge pipe operable from the locomotive tender for unlocking said discharge pipe.

3. A water column comprising a rigid vertical standpipe, a laterally extended discharge pipe connected for revolution about a vertical axis with the upper end of said standpipe, means for automatically and positively locking said discharge pipe from revolution whenever it is brought into a position parallel with the tracks, and a cam member pivoted to said discharge pipe operable from the locomotive tender for unlock-

ing said discharge pipe, said unlocking means embodying a device to hold the locking means inoperative in unlocking position until the discharge pipe has been rotated.

4. A water column comprising a rigid vertical standpipe, a laterally extended discharge pipe at the upper end thereof, means forming a water-tight revoluble joint between them at the top of the standpipe, and a supporting ballbearing for the discharge pipe surrounding, concentric with, and spaced from said joint.

5. A water column comprising a rigid vertical standpipe, a ring support connected with the standpipe and spaced from the outer cylindrical surface thereof, a second ring support revolubly connected with the first ring support by a ball-bearing and having a portion extending into said space with an inner cylindrical face surrounding and spaced from said outer cylindrical face, packing in the annular space between said faces, and a laterally extended discharge pipe rigidly connected with the second ring support.

6. A water column comprising a rigid vertical standpipe, a ring support connected with the standpipe and spaced from the outer cylindrical surface thereof, a second ring support revolubly connected with the first ring support and having a portion extending into said space with an inner cylindrical face surrounding and spaced from said outer cylindrical face, packing in the annular space between said faces, and a laterally extended discharge pipe rigidly connected with the second ring support.

7. A water column comprising a rigid vertical standpipe, a ring support connected with the standpipe and spaced from the outer cylindrical surface thereof, a second ring support revolubly connected with the first ring support and having a portion extending into said space with an inner cylindrical face surrounding and spaced from said outer cylindrical face, packing rings in the annular space between said faces, means for adjustably applying pressure to the packing rings to make a water-tight joint, and a laterally extended discharge pipe rigidly connected with the revoluble ring support.

8. A water column comprising a rigid vertical standpipe, a ring support connected with the standpipe and spaced from the outer cylindrical surface thereof and having an open-sided annular groove extending around the side of the ring, a second ring support having a portion over-lapping said first ring with an annular open sided groove on the inside thereof facing said first named groove, and having another portion extending into said space with an inner cylindrical face surrounding and spaced from said outer cylindrical face, a multiplicity of balls in

- the raceway formed by the two grooves providing both vertical and lateral support for the second ring, packing rings in the annular space between said cylindrical faces, 5 means carried by the second ring for adjustably applying pressure to the packing rings to make a watertight joint, and a laterally extended discharge pipe integrally connected with the second ring support.
- 10 9. A water column comprising a rigid vertical standpipe, a ring support connected with the standpipe and spaced from the outer cylindrical surface thereof, a second ring support revolvably connected with the 15 first ring support and having a portion extending into said space with an inner cylindrical face surrounding and spaced from said outer cylindrical face, packing rings in the annular space between said faces, a 20 pressure ring engaging said packing rings and adjustably secured to the second ring support for applying pressure to the packing rings to make a water-tight joint, and a laterally extended discharge pipe rigidly 25 connected with the revoluble ring support.
10. A water column comprising a rigid vertical standpipe, a laterally extended discharge pipe and a support therefor revolvably mounted on the standpipe, a pair of dogs 30 pivotally connected with the standpipe, and a lug on said support engageable with the dogs to hold the discharge pipe locked in parallel-track position.
11. A water column comprising a rigid vertical standpipe, a laterally extended discharge pipe and a support therefor revolvably mounted on the standpipe, a pair of dogs 35 pivotally connected with the standpipe, a lug on said support engageable with the dogs to hold the discharge pipe locked in parallel-track position, and means operable from the locomotive tender to withdraw the dogs from engagement with the lug.
12. A water column comprising a rigid vertical standpipe, a laterally extended discharge pipe and a support therefor revolvably mounted on the standpipe, a pair of dogs 40 pivotally connected with the standpipe, a lug on said support engageable with the dogs to hold the discharge pipe locked in parallel-track position, and means operable from the locomotive tender to withdraw the dogs from engagement with the lug.
13. A water column comprising a fixed standpipe, a support revolvably mounted on the standpipe and having a laterally extended discharge pipe connected therewith, a lug carried by said support, and a pair of dogs 45 pivotally connected with the standpipe and normally held so as to engage both sides of said lug to hold the discharge pipe 50 locked in parallel-track position.
14. A water column comprising a fixed standpipe, a support revolvably mounted on the standpipe and having a laterally extended discharge pipe connected therewith, a pair of dogs pivotally connected with the standpipe, said dogs comprising weighted ends for holding the same in operative position and feet having surfaces spaced from one another and extending substantially perpendicular, and a lug carried by the support 55 having the sides thereof engageable by said feet to hold the discharge pipe locked in parallel track position.
15. A water column comprising a fixed standpipe, a support revolvably mounted on the standpipe and having a laterally extended discharge pipe connected therewith, a lug carried by said support, and a pair of dogs pivotally connected with the standpipe, said dogs comprising weighted ends 60 for holding the same in operative position and feet having surfaces spaced from one another and extending in substantially perpendicular planes for engaging both sides of said lug to hold the discharge pipe locked in parallel-track position, and means operable from the tender to move said dogs on their pivots so as to withdraw the feet from engagement with the lug.
16. A water column comprising a rigid vertical standpipe, a laterally extended discharge pipe and a support therefor revolvably mounted on the standpipe, a pair of dogs 65 connected with the standpipe and movable relatively to said support, means on the support adapted to coöperate with the dogs to hold the discharge pipe locked in parallel-track position, and means operable from the locomotive tender to move the dogs and unlock the discharge pipe.
17. A water column comprising a rigid standpipe, a laterally extended discharge pipe, a member revolvably connecting the standpipe with the discharge pipe embodying a depending flange having an annular 70 surface in a horizontal plane, and a lug extended downwardly relative to said surface, a pair of dogs connected with the standpipe having portions movable relatively to said annular surface for engagement with said lug to hold the discharge pipe in parallel-track position, and means operable from the locomotive tender to move said portions from engagement and unlock the discharge pipe.
18. A water column comprising a rigid standpipe, a laterally extended discharge pipe, a member revolvably connecting the standpipe with the discharge pipe embodying a depending flange having an annular 75 surface in a horizontal plane, and a lug extended downwardly relative to said surface, a pair of dogs connected with the standpipe having portions movable relatively to said annular surface for engagement with said lug to hold the discharge pipe in parallel-track position.

lug to hold the discharge pipe in parallel-track position, means operable from the locomotive tender to move said portions from engagement and unlock the discharge pipe, 5 and means operative after said engagement to hold said portions in unlocking position.

19. A water column comprising a rigid standpipe, a laterally extended discharge pipe revolvably mounted on the standpipe, a 10 lug connected with the discharge pipe, a pair of dogs connected with the standpipe and co-operating with the lug to hold the discharge pipe locked in parallel-track position, and a cam piece connected with the discharge 15 pipe for controlling said dogs.

20. A water column comprising a rigid standpipe, a laterally extended discharge pipe revolvably mounted on the standpipe, a lug connected with the discharge pipe, a 20 pair of dogs connected with the standpipe and co-operating with the lug to hold the discharge pipe locked in parallel-track position, and a swinging cam piece connected with the discharge pipe for controlling said dogs, 25 said cam piece being operable upon the dogs when swung in either direction, and a projecting arm on the cam piece adapted to be engaged from the tender of an engine on a track at either side of the standpipe for 30 swinging the cam piece.

21. A water column comprising a rigid standpipe, a laterally extended discharge pipe revolvably mounted on the standpipe, a lug connected with the discharge pipe, a pair 35 of dogs connected with the standpipe and co-operating with the lug to hold the discharge pipe locked in parallel-track position, and a movable member having a cam surface adapted to engage said dogs and remove them from 40 locking co-action with the lug to release the discharge pipe.

22. A water column comprising a rigid standpipe, a laterally extended discharge pipe revolvably mounted on the standpipe, a 45 lug connected with the discharge pipe, a pair of dogs connected with the standpipe and co-operating with the lug to hold the discharge pipe locked in parallel-track position, a movable member having a cam surface adapted 50 to engage said dogs and remove them from locking co-action with the lug to release the discharge pipe, and means adapted to be operated from the tender of a locomotive at either side of the standpipe to move said 55 member.

23. A water column comprising a rigid standpipe, a laterally extended discharge pipe revolvably mounted on the standpipe, a lug connected with the discharge pipe, a pair 60 of dogs connected with the standpipe and co-operating with the lug to hold the discharge pipe locked in parallel-track position, a symmetrically disposed swinging cam piece connected with the standpipe and having a cam 65 surface overlying a pair of projections from

said lugs so as to engage and move said lugs into unlocking position when the cam piece is swung in either direction.

24. A water column comprising a rigid standpipe, a laterally extended discharge 70 pipe revolvably mounted on the standpipe, a lug connected with the discharge pipe, a pair of dogs connected with the standpipe and co-operating with the lug to hold the discharge pipe locked in parallel-track position, a symmetrically disposed swinging cam piece connected with the standpipe and having a cam surface overlying a pair of projections from 75 said lugs so as to engage and move said lugs into unlocking position when the cam piece is swung in either direction, and having cam notches formed on each side of said cam surface to receive said projections and hold the two dogs fixed in unlocking position.

25. A water column comprising a rigid standpipe, a laterally-extended discharge 80 pipe revolvably mounted on the standpipe, a lug connected with the discharge pipe, a pair of dogs connected with the standpipe and co-operating with the lug to hold the discharge 85 pipe locked in parallel-track position, a symmetrically-disposed swinging cam piece connected with the standpipe and having a cam surface overlying a pair of projections from 90 said lugs so as to engage and move said lugs 95 into unlocking position when the cam piece is swung in either direction, and having cam notches formed on each side of said cam surface to receive said projections and hold the two dogs fixed in unlocking position, said 100 cam notches each embodying an end wall to limit swinging movement of the cam piece in either direction.

26. A water column comprising a fixed standpipe, a laterally-extended discharge 105 pipe and a support therefor revolvably mounted on the standpipe, a lug on the support, and means automatically brought into engagement with the lug whenever the discharge pipe and its support are swung into parallel- 110 track position for holding said discharge pipe positively and fixedly locked.

27. A water column comprising a fixed standpipe, a laterally-extended discharge 115 pipe and a support therefor revolvably mounted on the standpipe, a lug on the support, means engageable with the lug to hold the discharge pipe positively and fixedly locked in parallel-track position, and means to move said engaging means and lug relatively to release the support and the discharge spout.

28. A water column comprising a fixed standpipe, a laterally extended discharge 125 pipe, a concentric supporting bearing for the discharge pipe spaced from its junction with the standpipe, and means forming a water-tight joint between the standpipe and the discharge pipe, and means for adjusting said joint, said supporting-bearing being 130

constructed and arranged to permit access to the adjusting means through the bearing support.

29. A water column comprising a fixed standpipe ending in a joint part and an annular bearing part concentric therewith and spaced therefrom and comprising a plurality of separate posts spaced from the joint part, and a laterally extended revoluble discharge pipe having its foot formed with a joint part and a bearing part co-acting respectively with said first named parts.

30. A water column comprising a fixed standpipe ending in a joint part and an annular bearing part concentric therewith and spaced therefrom and comprising a plurality of separate posts spaced from the joint part, and a laterally extended revoluble discharge pipe having its foot formed with a joint part, a bearing part co-acting respectively with said first named parts, and means for adjustably holding packing between said joint parts so disposed as to be easily accessible from below the bearing part and between the supporting posts.

31. A water column comprising a rigid standpipe, a laterally-extended discharge pipe revolvably mounted on the standpipe, a

lug movably connected with the discharge pipe, means for yieldingly holding said lug in operative position, and a pair of dogs connected with the standpipe and adapted to co-operate with the lug to hold the discharge pipe locked in parallel-track position, said yielding means acting to relieve shock when either dog is forcibly brought into contact with the lug.

32. A water column comprising a rigid standpipe, a laterally-extended discharge pipe revolvably mounted on the standpipe, a lug movably connected with the discharge pipe, a piece pivotally connected to the discharge pipe having a downwardly-depend ing lug and laterally-extended arms, springs engaging said arms to hold the lug in normal operative position, a pair of dogs connected with the standpipe and adapted to co-operate with the lug to hold the discharge pipe locked in parallel-track position, said springs permitting yielding oscillatory movement of the lug to relieve shock when either dog is forcibly brought into contact with the lug.

In testimony hereof I affix my signature.

EDWARD E. JOHNSON.
